TELEVISION PROGRAM REMINDER

Leonard J. Littrell, Denver, and Hugh R. Vickers,
Edgewater, Colo.

Application March 16, 1955, Serial No. 35,073

Term of patent 14 years

(Cl. D1—2)

Fig. 1 is a perspective view of a television program reminder showing our new design; and

Fig. 2 is an end view thereof.

The dominant features of our design reside in the portions shown in full lines.

We claim:

The ornamental design for a television program reminder, as shown and described.
